CONED YARN SUPPORT

Carl Epps, Rome, Ga., assignor to Tubize
Chatillon Corporation, a corporation of Dela-
ware

Application February 24, 1934, Serial No. 712,747

4 Claims. (Cl. 242—130)

This invention relates to coned yarn supports and has for its object certain improvements in the construction of coned yarn supports. The invention relates more particularly to cone 5 gripping devices employed in the unwinding of coned yarn.

Yarn, threads, strands and the like are wound on a receiving device in the course of their manufacture. This device customarily consists 10 of a paper or pasteboard cone, bobbin, cap or similar object. During the course of manufacture of finished textile products, the coned yarn is unwound from a paper cone directly to, for example, a knitting machine or other 15 receiving device. In order to conduct the yarn unwinding operation in a continuous and satisfactory manner, it is necessary that the body of coned yarn be rigidly supported so that the unwinding yarn may be drawn to the knitting 20 machine with a minimum variation in tension. Various tension and cone gripping devices are employed in an effort to obtain this desired result. In the case of cone gripping devices such as are now generally employed, several 25 troublesome difficulties are often encountered. The cone gripping device may be adapted to receive and hold a paper cone of only one specific size. The cone gripping device may also have inadequate gripping surface firmly 30 to hold the cone in fixed position during the unwinding operation.

In the course of my investigations, I have discovered a cone support construction that largely overcomes the difficulties just enumerated. The 35 device is readily adjustable to receive cones of various shapes and sizes. A considerable amount of gripping surface is provided to be placed in contact with the inside contour of the cone so that the cone may be held in fixed position during 40 the entire unwinding operation.

The invention contemplates a yarn support comprising a spindle, a core member on the spindle and a plurality of adjustable cone gripping fingers mounted on the core member. In 45 a present preferred practice of the invention the core member is provided on its exterior with a plurality of spaced longitudinal slots, and the adjustable cone gripping fingers are loosely and pivotally mounted in those slots. The core member itself may be freely moved up 50 and down the spindle and secured at any desirable position. The pivoting cone gripping fingers are tiltable toward the upper end of the spindle, which places them in position readily 55 to receive a cone of substantially any practicable

contour. As the cone is pushed downwardly over and in contact with the fingers, they are promptly lined-up to conform with the taper of the cone. A substantial amount of friction surface is provided by the faces of the fingers in contact with the cone. The size and number of the fingers may of course be varied in order to provide the amount of friction surface required to operate under optimum conditions.

These and other features of the practice of 10 the invention will be more readily understood on inspecting the attached drawing, of which the following is a description:

Fig. 1 is a side elevation of a yarn supporting device including a cone gripping support illustrative of the present invention, together with an adjustable bracket and a tension device. A mounted cone is shown in section, which permits an interior view of the cone gripping support mounted on a spindle;

Fig. 2 is an enlarged detail and cross-sectional view of the spindle and core member of Fig. 1;

Fig. 3 is a section on the line 3—3 of Fig. 2;

Fig. 4 is an enlarged perspective view of one of the cone gripping fingers; and

Fig. 5 is an enlarged perspective view of the core member.

The construction shown comprises coned yarn 10 wound on a paper cone 11 supported over a spindle 12. The coned yarn rests on or closely 30 adjacent to a circular base support 13. This base support is advantageously so constructed that the yarn itself may rest on the same, while the lower and protruding end of the paper cone may freely extend downwardly. Such a construction is disclosed and claimed in my copending application Serial No. 712,746 filed February 24, 1934.

The above mentioned elements are supported by an adjustable bracket comprising a base link 40 14, two intermediate links 15 and 16, and a ballooning link 17 in series. Thumb screws 18, 19 and 20, respectively, are provided to fasten the links. The spindle is attached to the base link by means of lock nuts. Both intermediate links 45 are provided with threaded holes 21 and 22, respectively, to provide means for attachment to an ultimate support 23, such as a knitting machine, by means of a member 24 adapted to fit into said threaded holes.

A yarn guide 25, such as a porcelain eyelet, through which the yarn 26 may be drawn, is provided at the free end of the ballooning link. A tension device 27 is mounted on the same end 50 of the ballooning link. It consists of an upright 55

member 28 attached to the link by means of a screw 29. A movable arm 30 is attached to the upper end of the upright member by means of a screw 31. This arm is also provided with a yarn 5 guide 32, preferably a porcelain eyelet somewhat smaller than eyelet 25. The two yarn guides may be placed in co-axial alignment, or the alignment may be altered depending upon the amount of tension to be placed on the 10 winding yarn.

The specific cone gripping features of the invention will now be considered:

A hollow tapered core member 33 is mounted on spindle 12. It is threaded so that the core 15 member may be moved up and down the spindle. A threaded stud 34 extends through the shell of the core member so that the core may be securely locked to the spindle at a desired position. Referring more particularly to Fig. 5 it 20 will be seen that the core member is provided with a plurality of longitudinal slots 35, 35', 35'', each of which is adapted to receive a cone gripping finger 36. The core member is also provided with a circumferential slot 37, which is 25 adapted to receive a coiled tension spring 38. Figs. 1, 2 and 3 show the gripping fingers 36, 36', 36'' in position. In order to get a desired 30 pivotal action, the cone gripping fingers are constructed as shown more particularly in Figs. 2, 3 and 4. They are elongated and narrow, the sides next to the core member being provided with a curved protruding shoulder 39. A depression 40 is provided at the juncture of the longitudinal slots 35 and the circumferential 35 slot 37 in the core member to receive this protruding shoulder. The side of the cone gripping fingers opposite the protruding shoulder is provided with a transverse slot 41 adapted to register at least in part with the circumferential slot 37 in the core member. The cone gripping 40 fingers are advantageously rounded at their upper ends 42 more readily to receive a cone.

In operation thumb screw 20 is loosened, balloon link 17 is moved back out of the way, and 45 the upper ends of the cone gripping fingers 36, 36', 36'' are advantageously pushed toward the spindle 12 (see Fig. 2). The coned yarn 10 on its paper cone 11 is then moved in position over the spindle, and pushed downwardly over the 50 cone gripping fingers. It is preferred that the cone be pushed down sufficiently far so that the coned yarn itself may rest on the base support 13. In case the cone is not then sufficiently gripped, the cone is elevated and the core member 55 33 is moved upwardly along the spindle and locked in a position adapted to give the required frictional resistance between the gripping fingers and the inside of the cone. It will of course be clear that if the core member is too high on the spindle to permit the positioning of the coned yarn on the base support 13, the core member

should be moved toward the base of the spindle into a position best located to give optimum results. Due to the slanting direction of the cone gripping fingers in their normal position, the base of the cone may readily be pushed down over the fingers. Since the gripping fingers are pivotally mounted on the core member, they are promptly placed in face to face alignment with the inside of the cone.

I claim:

1. The improvement in a coned yarn support comprising a spindle, a core member, the spindle and core member being threaded so that the core member may be advanced on the spindle, said core member being exteriorly provided with 15 a transverse slot and a plurality of spaced longitudinal slots, cone gripping fingers loosely mounted in said longitudinal slots, said fingers each being provided with a transverse slot which registers with the transverse slot in the core member, and a flexible ring mountable in said transverse slots to hold said cone gripping fingers in pivotal position.

2. The improvement in a coned yarn support according to claim 1, comprising a flexible 25 ring of coiled spring wire to hold the cone gripping fingers in position.

3. In a coned yarn support, the improvement comprising a core member, said core member being exteriorly provided with a transverse 30 slot and a plurality of spaced longitudinal slots, cone gripping fingers loosely mounted in said longitudinal slots, said fingers each being provided with a transverse slot which registers with the transverse slot in the core member, and a 35 flexible member mountable in said transverse slots to hold the cone gripping fingers in pivotal position, said cone gripping fingers being provided with a cone contacting surface that extends substantially along their entire length 40 to afford an optimum amount of frictional resistance between the gripping fingers and the inside of a cone.

4. In a coned yarn support the improvement comprising a tapered core member, said core 45 member being exteriorly provided with a transverse slot and a plurality of spaced longitudinal slots conforming to the taper of the core member, elongated straight faced cone gripping fingers loosely mounted in said longitudinal slots, 50 said fingers each being provided with a transverse slot which registers with the transverse slots in the core member, and a flexible member mounted in said transverse slots to hold the cone gripping fingers in pivotal position, said 55 cone gripping fingers being provided with a cone contacting surface that extends substantially along their entire length to afford an optimum amount of frictional resistance between the gripping fingers and the inside of a cone.

CARL EPPS.
